corporation of Iowa

Application January 19, 1946, Serial No. 642,214

15 Claims. (Cl. 250—36)

1

This invention relates to automatic tuning control systems and more particularly to a method and means for controlling the frequency of an adjustable frequency electronic oscillator.

In certain types of high frequency signalling systems employing an adjustable frequency oscillator, it is requisite that the oscillator be stabilized at any one of its predetermined frequency settings, and oscillator "drift" must be reduced to a minimum. Drift may result in an oscillator operating at a frequency either slightly above or slightly below the desired frequency setting. In order to restore the oscillator automatically to the desired frequency, it is necessary to employ some tuning control means which will respond not only to the magnitude of drift but also to direction or polarity of drift.

Accordingly, it is a principal object of this invention to provide a frequency responsive system which will immediately correct any undesired frequency deviations of an adjustable frequency oscillator.

It is another object of this invention to provide electromechanical control means for overcoming oscillator frequency drift in either direction with respect to the desired frequency setting of the oscillator.

It is another object of this invention to provide an electronic control circuit for controlling the direction and duration of rotation of a drift control motor.

It is a further object of this invention to provide an automatic oscillator tuning system wherein the direction of rotation of a tuning motor is determined by a plurality of electronically operated relays and wherein an electronic circuit determines the direction in which said tuning motor must be rotated to retune the oscillator, said direction of rotation being determined by the frequency of the energy which the frequency drift introduces into the system.

One of the features of this invention is a unique circuit arrangement which is non-operative when the oscillator is on frequency and which actuates instantly a rotatable oscillator tuning control motor when the oscillator begins to drift and if the initial direction of rotation of the motor be incorrect, reverses that rotation. In either case rotation of the motor continues until the oscillator is retuned to its original desired frequency setting.

It is another feature of this invention that energy introduced into the electronic circuit from the frequency drift of the oscillator is fed into a differentiating circuit which determines whether

2

the frequency is increasing or decreasing while the motor is rotating the tuning means of the adjustable frequency oscillator.

It is a further feature of this invention that a positive or increasing output voltage results from the differentiating circuit if the tuning motor tends to increase the frequency deviation of the oscillator, and this increasing output voltage energizes a relay which causes the tuning motor to reverse its direction of rotation so as to retune the oscillator to the desired frequency setting.

Other features and advantages not particularly enumerated will become apparent after a consideration of the following detailed description and the appended claims.

The drawing is a schematic wiring diagram which shows one preferred manner of practising the invention.

20 Referring more particularly to the drawing, the adjustable frequency oscillator 10 includes a tunable oscillatory circuit 11 and a grid-controlled vacuum tube such as triode 12. The frequency of oscillation of the circuit 11 is determined by varying the inductance 13 for large increments of frequency and varying the condenser 14 for small increments of frequency. Inductance 13 is ganged, as represented by the dotted line, to inductance 15 which together with parallel condenser 16 provides a tuned input circuit connected across the first control grid 17 and cathode 18 of mixer tube 19. The output of tube 12 is divided, one portion being from plate 20 through conductor 21, to supply the carrier for any well-known radio transmitter 22, the other portion is fed from plate 20 to grid 17. The electronic calibrator 24 provides a second source of radio frequency energy of known accurate frequency such as a piezo crystal-controlled oscillator. The output of calibrator 24 is fed to the second control grid 25 of mixer tube 18. The calibrator 24 may be a multi-vibrator or other well-known means by which stable radio frequency waves suitable for calibration are produced.

45 The audio-frequency transformer 26 applies the beat frequency output from plate 27 to control grid 28 of audio-frequency amplifier tube 29. When the frequency of the calibrating waves impressed on grid 25 is the same as the output frequency of the oscillator 10 impressed on grid 17, there will be no audio frequency beat note present in the output of mixer 19.

If the frequency of the adjustable frequency oscillator 10 changes for any reason, an audio beat frequency appears across the secondary 30

of transformer 26. In accordance with the invention, the plate current of tube 29 is made proportional to the frequency deviation of oscillator 10. For this purpose, resistor 31 and inductance 32 form a frequency responsive network which acts upon any audio-frequency signals applied thereto, so that when the output of tube 29 is substantially zero there is no beat frequency and the output increases as the beat frequency increases. The audio frequency output of tube 29 may be further amplified by the amplifier tube 33.

Control grid 34 of amplifier tube 35 is normally biased negatively to prevent plate current conduction through that tube. However, when an audio beat frequency appears across the secondary of transformer 26, the negative bias on grid 34 is overcome sufficiently to cause plate current to flow through tube 35. The winding of electromagnetic relay 37 is included in the plate circuit of tube 35, and this relay thereupon operates. The closing of the contacts of relay 37 completes a circuit traceable from the positive D. C. terminal 38, conductor 39, winding of relay 40, conductor 41, thence to the negative terminal 42. Relay 40 thereupon closes the power circuit from the line terminals 43, 44, to the armature of the motor. At the same time, the field winding 45 of the motor is connected in parallel with the armature 46, through the armatures 47, 48, and the respective back contacts of directional control relay 49. The motor rotates the adjustable element 14, and thereby changes the frequency of the oscillator 10 and the signals fed to grid 17. If the direction of rotation of the motor is not such as to restore the oscillator 10 to its proper frequency as determined by the calibrated setting of device 24, additional means are provided to insure that even though the motor should begin to rotate in the wrong direction, its direction of rotation is substantially immediately reversed to cause it to rotate to bring the oscillator back to the proper frequency. For this purpose, the output of amplifier 33 is also applied to the rectifier tube 50 through audio frequency transformer 51. In other words, if the motor is rotating in the wrong direction, an increasing D. C. current flows through the primary of transformer 52; while if the direction of motor rotation is correct, a decreasing current flows through this primary. This change of current through transformer 52 causes either a positive or a negative voltage to appear at grid 53 of amplifier tube 54. Tube 54 has its control grid normally biased so as to prevent the operation of relay 55 when a zero or negative voltage appears at transformer 52. On the other hand, when a positive voltage appears at that transformer, sufficient plate current flows through tube 54 to operate relay 55. The instant relay 55 operates, it immediately closes a locking circuit for itself traceable from positive terminal 38, winding of relay 55, armature 59, contact 60, to the negative terminal 42 through the contacts of relay 37. It will be noted therefore, that this locking circuit remains closed so long as relay 37 is operated, that is to say, so long as any beat frequencies appear at transformer 26. Likewise, this locking circuit remains independent of the rectifier 50 and the amplifier tube 54.

When relay 55 operates, it closes a circuit traceable from the negative terminal 42, contact 57 and associated armature 56, winding of relay 49, conductor 39, to the positive terminal 38. Relay 49 operates its contacts and in doing so reverses the connections from the power line

terminals 43, 44, to the field winding 45, thereby reversing the direction of rotation of motor 34, and causing it to tune the oscillator towards its proper frequency. As the motor continues to rotate in the proper direction, the frequency deviation of oscillator 10 with respect to calibrator 24, is correspondingly reduced. This results in a decrease in the beat frequency appearing at transformer 26. When the frequency deviation approaches zero, insufficient current flows through relay 37 with the result that this relay opens its contacts and therefore opens the locking circuit of relay 55. Relay 55 thereupon releases as does relay 40, thus opening the power circuit to the motor. From the foregoing, it will be seen that the relay 55 is in effect a directional sensitive relay. That is to say, it is initially energized only when the motor is actually rotating in the wrong direction tending to increase the frequency deviation of the oscillator. However, once energized, it remains locked until the deviation is reduced to zero. It provides therefore a positive check or limit on the amount of undesirable initial rotation of the motor and at the same time it provides a positive automatic control of the reversal of direction of the motor so as to reduce to zero the frequency deviation of the oscillator with respect to calibrator 24.

It is desirable to have some visual frequency indicating means which may be used to facilitate the manual tuning of the oscillator and mixer stages. Therefore, any suitable frequency indicating device such as a calibrated dial may be suitably mechanically connected to the shafts of the adjustable elements 13 and 15. After accurate tuning is once accomplished by adjusting manually elements 13 and 15, the automatic control means above described will keep the oscillator 10 in accurate adjustment.

While there has been here described a preferred embodiment of this invention, it is understood that various changes and modifications may be made therein without departing from the scope of the invention, as defined in the following claims.

What is claimed is:

1. In combination, an oscillator for generating a voltage of adjustable frequency, a source for producing another voltage of a certain standard frequency, a mixer network upon which signals from said oscillator and said source are simultaneously impressed to produce an oscillator tuning control voltage proportionate to the frequency difference between said oscillator and said source, a motor for controlling said oscillator, a directional control device for determining the direction of rotation of said motor, a relay arrangement responsive to said tuning control voltage above a predetermined minimum to cause said motor to rotate, and another relay arrangement responsive to an increase in said tuning control voltage resulting from the starting of said motor in the wrong direction to operate said directional control device to reverse the motor rotation until said oscillator is at the desired frequency.

2. In combination, an oscillator for generating a voltage of adjustable frequency, a source for producing another voltage of a certain standard frequency, electron tube mixer means for combining said voltages to produce a tuning control voltage which is proportionate to the difference between the frequency of the voltages from said oscillator and from said source, a first relay which responds to said tuning control voltage

above a predetermined minimum, a second relay which responds to a change in the magnitude of said tuning control voltage corresponding to an increase in said frequency difference, means to adjust a tuning control element of said oscillator, and reversible switching contacts controlled by the joint operation of said first and second relays for determining the direction of adjustment and the extent of the adjustment of said adjusting means.

3. In combination, an oscillator for generating a voltage of adjustable frequency, a source for producing another voltage of a certain standard frequency, means to mix said voltages to produce a tuning control voltage which is proportionate to the difference between the frequency of said oscillator and that of said source, the last-mentioned means including a frequency discriminator network, a relay connected to said network which responds to said voltages above a predetermined minimum, means to rectify said voltages to produce a uni-directional voltage only when said first-mentioned voltage is varying, another relay responsive to said uni-directional voltage and whose energizing circuit is controlled by said uni-directional voltage, a locking circuit for said second-mentioned relay which locking circuit is independent of said uni-directional voltage but is controlled by the first-mentioned relay, means to adjust a movable tuning element of said oscillator, and a motor device for controlling the direction and extent of said adjusting movement, said motor device being controlled jointly by said first and second-mentioned relays.

4. In a frequency control system, a frequency combining network to derive a tuning control voltage proportionate to the deviation of an oscillator from a standard frequency, circuit arrangements including a relay which responds to said voltage above a predetermined minimum, a motor for adjusting said oscillator, a starting control relay and a direction control relay for controlling the power circuit of said motor, circuit connections for applying said voltage to cause one of said pair of relays to control the initial starting of said motor, and for causing the other of said pair of relays to control the direction of rotation of said motor, means to operate the said starting control relay in response to the operation of the first-mentioned relay, and means to operate the direction control relay only when said voltage tends to increase as a result of the starting of the operation of said motor in the wrong direction.

5. A frequency control system according to claim 4 in which an additional relay is provided for controlling the initial energization of said direction control relay, said additional relay being energized only when said voltage tends to increase as a result of the starting of rotation of said motor in the wrong direction.

6. In a frequency control system, a frequency combining network to derive beat frequencies corresponding to the output of an adjustable oscillator and a standard frequency source, a frequency discriminator network including an electron discharge tube amplifier upon which said beat frequencies are impressed, a relay which is energized by the output of said amplifier above a predetermined minimum, a rectifier for rectifying a portion of said beat frequencies, a grid-controlled amplifier tube normally biased substantially to plate current cutoff and responsive to positive rectified voltages from said rectifier

to produce plate current flow, a second relay which is initially energized in response to said plate current flow, a locking circuit for said second relay including contacts of the first relay which locking circuit is independent of said rectified beat frequencies, a motor control relay which is operated under control of said first relay, a motor reversing relay which is operated in response to the operation of said second relay, and circuit arrangements for causing said motor control relay to be operated only when the initial direction of rotation of said motor is such as to increase said beat frequencies, so as to reverse the rotation of said motor to a direction to reduce said beat frequencies.

7. In a frequency control system, an electron tube oscillator having a frequency-determining circuit connected thereto, a source of standard frequency oscillations, a mixer tube having a tunable input circuit connected to one control grid thereof, said input circuit being tuned in unison with the tuning of said frequency-determining circuit, means to impress said standard frequency oscillations on another control grid of said mixer tube to produce audio-frequency beats in the output of said mixer tube corresponding to the deviation between the frequency of said oscillator and said standard source, a frequency discriminator network connected to the output of said mixer tube, a grid-controlled amplifier tube normally biased to plate current cutoff, and means connecting the control grid of said tube to the output of said network to produce plate current when the output of said network is above a predetermined minimum, an electromagnetic relay controlled by the plate current of said grid-controlled tube, a motor starting relay controlled by said electromagnetic relay, a second grid-controlled tube normally biased substantially to plate current cutoff, means to produce positive D. C. voltages proportionate to the output of said amplifier, means to apply said positive D. C. voltages to the grid of said second grid-controlled tube to cause plate current to flow therethrough, another electromagnetic relay which is initially energized in response to an impulse of plate current through said second grid-controlled tube, a locking circuit for said second electromagnetic relay which is closed through the contacts of the first-mentioned electromagnetic relay so as to be independent of said second-mentioned grid-controlled tube, and a motor reversing relay which is controlled by said second-mentioned electro-magnetic relay.

8. The method of adjusting the frequency of an adjustable oscillator which comprises, producing a voltage which is proportionate to the deviation of said oscillator from a known standard frequency, operating a tuning element of said oscillator in response to said voltage, producing another voltage which corresponds to an increase in said deviation, and applying the second-mentioned voltage to determine the direction of operation of said tuning element.

9. In a frequency control system, means to produce beat frequencies corresponding to the frequency deviation of an adjustable oscillator with respect to a standard frequency source, a first electromagnetic relay responsive to the presence of said beat frequencies, a motor for adjusting a tuning element of said oscillator, a second electromagnetic relay for controlling the starting of said motor, a third electromagnetic relay for controlling the direction of rotation of said motor, and a fourth electromagnetic relay

for determining the duration of rotation of said motor, said relays being interconnected so that said motor responds initially to the presence of said beat frequencies and its direction of rotation is automatically corrected so as to reduce said beat frequencies substantially to zero.

10. An oscillator system including an adjustable frequency electron tube oscillator, including an adjustable frequency-determining element, a motor connected to said element to vary the oscillator frequency, a source of standard frequency, a frequency mixer adapted to produce a zero beat frequency only when the signal received by it from said oscillator is substantially equal to the signal received by it from said standard source, a frequency sensitive network having an output which varies in correspondence with the frequency of the energy received by it from said mixer, a control circuit connected to the output of said frequency sensitive circuit, said control circuit being effective when said mixer produces an output to complete the power circuit to said motor, said control circuit also including a motor reversing control relay, directional differentiating means comprising an electron tube arrangement for converting a part of the output of said network into a voltage whose polarity is dependent upon whether said motor is rotating in a direction tending to produce said zero beat frequency, or it is rotating in a direction tending to increase said beat frequency, and means to operate said reversing switch contacts only when said motor starts to rotate in a direction tending to increase said beat frequency.

11. A system according to claim 10 in which said directional differentiating means includes a rectifier for rectifying a portion of the output of said frequency-sensitive network, and a grid-controlled electron tube which is normally biased to plate current cutoff and which remains at plate current cutoff only while the output of said rectifier is decreasing.

12. A system according to claim 10 in which said reversing control relay is connected in the output of said electron tube arrangement.

13. An automatic frequency-controlled electronic oscillator system including an oscillator for

- generating a voltage of an adjustable frequency, a source for producing another voltage of a certain standard frequency, a tuning motor for said oscillator, a frequency mixer connected to said oscillator and source to produce a beat frequency corresponding to the deviation of said oscillator from a pre-assigned frequency, a beat frequency responsive circuit arrangement connected to the output of said mixer and effective to cause operation of said motor only when a beat frequency exists at the output of said mixer, said beat frequency responsive circuit including a motor starting relay which closes the motor circuit in response to a beat frequency and a motor directional control relay which responds only when the motor is started in a direction tending to increase said beat frequency.
14. A system according to claim 13 in which said motor start relay has a locking circuit which is completed through the normally open contacts of said directional control relay.
15. In an automatically tuned oscillator system, means to produce a variable beat frequency corresponding to the departure of the oscillator from a pre-assigned frequency, an electron tube network to which said beat frequency is applied for producing in its output a control signal whose amplitude varies with the frequency of the beat, a motor for tuning the oscillator, a relay which operates in response to the presence of a beat frequency, another relay connected to the output of said network and operated only when the motor rotates in a direction tending to increase said beat frequency, and a third relay for controlling the direction of rotation of the motor, said third relay being operated under the joint control of the first and second relays.
